A technical line drawing of a mechanical assembly, possibly a flywheel or wheel mechanism. The drawing shows a large, hatched wheel body with a central hub. A vertical shaft or pin 157 extends from the top of the wheel. A horizontal lever or arm 155 is attached to the side of the wheel. A small pin 153 is located on the side of the wheel body. A lever 156 is attached to the side of the wheel body. A small pin 150 is located on the side of the wheel body. A lever 136 is attached to the side of the wheel body. A small pin 148 is located on the side of the wheel body. A lever 115 is attached to the side of the wheel body. A small pin 106 is located on the side of the wheel body. A lever 47 is attached to the side of the wheel body. A small pin 135 is located on the side of the wheel body. The drawing is labeled "Fig. 10." in cursive script.

UNITED STATES PATENT OFFICE.

SIMON SCHLANGEN, OF CHICAGO, ILLINOIS.

FILLING APPARATUS FOR LIQUIDS.

SPECIFICATION forming part of Letter : Patent No. 784,596, dated March 14, 1905.

Application filed February 4, 1904. Serial No. 191,997.

To all whom it may concern:

Be it known that I, SIMON SCHLANGEN, a citizen of the United States, residing at Chicago, in the county of Cook and State of Illinois, 5 have invented certain new and useful Improvements in Filling Apparatus for Liquids, of which the following is a specification.

The invention relates more particularly to apparatus for filling barrels, kegs, and similar packages with liquid, such as beer, under pressure, and has for its objects to improve the suspending means by which the closing-head and filling-tube are carried, so as to insure the proper contact of the closing-head 10 with the bung-hole or filling-hole of the barrel, keg, or package, to insure the positive opening of the valve controlling the discharge of the filling-tube when the filling-tube has reached the limit of its descent, to improve 15 the construction and operation of the appliance carrying the closing-head and the filling-tube in connection with a fluid-pressure cylinder having therein a piston by which the cross-heads carrying the closing-head and the filling-tube are raised and lowered, to utilize 20 the waste pressure from the filling-package in actuating the piston by which the closing-head and the filling-tube are raised and lowered, to place the control of the pressure and 25 the liquid under a single valve, to improve the construction and operation of the valve by which the fluid-pressure and the liquid are controlled, to improve the means by which the inflow and outflow of the pressure between 30 the filling-tank and the to be filled package is regulated and controlled, to prevent 35 the foaming of the liquid within the package and insure the filling of the package with the liquid to its full capacity without waste of 40 liquid, to furnish an intermediate controlling means for the pressure between the one controlling-valve and the to be filled package by which the flow of the pressure in either direction will be regulated and controlled, to 45 furnish a relief-valve by means of which the requisite amount of pressure from outside will be supplied to prevent an explosion at the withdrawal of the filling-tube, and to improve generally the construction and operation 50 of the several parts and mechanisms

which enter into the construction of the apparatus as a whole.

The invention consists in the features of construction and combinations of parts hereinafter described and claimed. 55

In the drawings, Figure 1 is an elevation of an apparatus employing three filling-tubes and appliances for operating in connection with three packages, one of the closing-heads and filling-tubes being shown raised with a package in place, another of the closing-heads and filling-tubes being shown depressed with the package removed, and the third one of the closing-heads and filling-tubes being shown depressed with the package in section; 60 Fig. 2, an elevation, partly in section, showing one filling apparatus and the end of the filling-tank; Fig. 3, a similar view to Fig. 2, showing the closing-head and the filling-tube lowered; Fig. 4, a side elevation of one filling apparatus with the filling-tank in section; Fig. 5, a sectional plan view of one of the suspending-heads for a filling apparatus, showing one end of the tank in plan, with some of the fluid-pressure tubes broken off; Fig. 6, a 65 detail in section of the lower cross-head of the suspending-frame carrying the closing-head and the filling-tube; Fig. 7, a sectional elevation of the single controlling-valve for the fluid-pressure; Fig. 8, a cross-section on line 8 of Fig. 7, showing the position of the ports and passages for the direct admission of fluid-pressure; Fig. 9, a similar view to Fig. 8 on line 9 of Fig. 7, showing the position of the ports and passages for admitting fluid-pressure to the intermediate controlling device between the single controlling-valve and the closing-head; Fig. 10, a cross-section through the single controlling-valve, showing the valve-plug in position to close the ports and passages 70 for supplying pressure to the operating-cylinder of the filling-tube and leave open the ports and passages for the flow of pressure through the valve to the controlling-cylinder; Fig. 11, a sectional elevation of the intermediate controlling means for the fluid-pressure between the single controlling-valve and the closing-head; Fig. 12, a detail in sectional plan of the controlling-head and the passages therein for fluid-pressure; Fig. 13, a detail in section 75 80 85 90 95 100

showing an elevation of the vent-valve by which pressure from the outside is admitted to the intermediate controlling means with the withdrawal of the filling-tube to prevent 5 explosion; Fig. 14, a side elevation of the tripping means for opening the discharge-valve of the filling-tube, showing the parts in the position when the valve is closed; Fig. 15, a sectional elevation of the tripping device, 10 showing the parts in position with the valve at the discharge end of the filling-tube open; Fig. 16, a plan view, partly in section, of the tripping device for the valve of the filling-tube; and Figs. 17 to 26 outline views showing the 15 several positions of the controlling-valve.

The apparatus in the construction shown has end legs or standards 1, to the tops of which are secured end supports 2, which receive and carry the filling-tank 3, made of 20 metal or other suitable material and of a length to coat with one or more filling appliances, the construction shown having a tank of a length sufficient to coat with three filling appliances. The tank at one end has a fixed 25 head 4 and at the other end has inserted therein a rim or flange 5, against which abuts a removable head 6 to enable access to be had to the interior of the filling-tank. The end standards are connected on the front side by a plate 30 or bar 7, the ends of which are secured to the supports by bolts 8 or otherwise.

The plate or bar 7 furnishes the support for suspending each filling apparatus, and each filling apparatus and the suspension means 35 therefor are of the same construction, so that the description of one will describe all. At a suitable distance apart the plate or bar 7 has secured thereto two companion bracket-plates 9, each bracket-plate having on opposite sides 40 thereof ears 10 for the passage of bolts 11, by which each plate is secured to the plate or bar 7, and each bracket-plate has on one side edge running from its face to the ear a strengthening-flange 12 in the construction shown. Each 45 bracket-plate has formed therewith in the arrangement shown a half box or bearing 13, the companion half box or bearing 14 of which is attached by ears 15 and bolts 16 to the bracket-plate 9, so as to make a complete journal box or bearing. Between the two companion bracket-plates is located a frame 17, 50 having straight sides and curved ends, and each end has a journal 18 to enter the journal-box of the adjoining bracket-plate, so that the frame 17 is free to rock fore and aft on its journals. Each side bar of the frame 17 has formed therewith or suitably secured thereto a half box or bearing 19, and a companion half box or bearing 20 coöperates with 55 the half box or bearing 19 to make a complete box or bearing. The two half boxes or bearings are connected together by ears 21 on the half box or bearing 19 and ears 22 on the half box or bearing 21, which ears extend beneath 60 the end edge of the side bar of the frame 17

and bolts 23. A plate 24 is located within the interior of the frame 17 and on each opposite side has a journal 25 to enter the journal box or bearings on the frame 17, so that the plate 24 is free to tip or rock endwise on its journals. This arrangement of the frame 17 and plate 24 furnishes a support which has a fore-and-aft rock and an end rock by which the closing-head can be brought into position to properly coat with the bung or other filling 75 hole in the package in the event such bung or other filling hole is not in direct alinement with the closing-head and the filling-tube. 7c

The plate 24 has on each side depending flanges 26, and extending down from each end of the plate 24 is a bar 27, and each bar has outwardly projecting near its upper end an ear 28, through which passes an adjusting-screw 29, the end of which can be set nearer to or farther from the face of the under edge 85 of the frame 17, so as to limit the end rock of the plate 24 on its journals, and thereby limit the side swing of the bars 27 at the lower end, and consequently the side swing of the closing-head and filling-tube. The lower end 90 of each side bar 27 has on its outer face an ear 30 and on its inner face a lug 31, and the lower ends of the side bars are connected together by a cross-bar 32, which, as shown, has a rearward projection, so as to leave a clear 95 space between the side bars at their lower ends, as shown in Fig. 6. One of the lugs 31 has extending out therefrom a head 33, projecting inwardly from which is a plate 34, through which the filling-tube passes and by 100 which the filling-tube is guided in its reciprocating movements.

A cross head or plate 35 is located below the cross head or plate 32, and this plate 35 at each end has entered therein the lower end 105 of a rod 36, and each rod is free to slide up and down in a thimble 37, entered into the lug 31, and each rod is fixedly attached at its lower end to the cross head or plate 35 by nuts 38 and 39 on opposite sides of the cross head or plate. Each rod 36 extends upwardly 110 and projects above the plate 24, passing through thimbles 40, and each rod at its upper end has slipped thereon a weight 41, held in an adjusted position by a flange or nut 41a or other suitable means, which weights, in connection with the rods and cross head or plate 35, normally act to force or carry down the cross head or plate 35 to set the closing-head 115 in the bung or other filling hole in the package. 120

The cross-head 35 on each side of its center has an enlarged portion 42 and at its center has a circular portion 43 in the construction shown, and depending from the circular portion of the cross head or plate 35 is an annular and conical shaped boss 44, terminating in an annular lip or flange 45, the inner face of which is outwardly and upwardly inclined and receives a packing 46, of india-rubber or other suitable material. The packing 46 is 130

entered into a groove formed in the outer face of a bushing 47, the lower end of which terminates in a ridge 48, having a curved exterior face, so as to facilitate the entering of 5 the packing into the bung or other hole, so as to tightly close the same. The bushing 48 in its interior face has a series of slots or passages 49 extending from the top to the bottom of the bushing, and the bushing on the 10 exterior around its upper end has a thread, by means of which it is screw-threaded into an opening therefor in the circular portion of the cross head or plate 35. The slots or 15 passages 49 at their upper end open into an annular chamber 50, from which on one side in the enlarged portion of the cross head or bar 35 leads a passage 51, through which passage and the chamber and the slots or passages fluid-pressure can be admitted into and 20 escape from the to-be-filled package.

The filling-tube 52 for the liquid passes through the circular portion of the cross head or plate 35 and is surrounded by the annular chamber 50 and is guided in its reciprocating 25 movements by the bushing 47, so that the filling-tube will have a direct line movement and a firm support in being entered into and withdrawn from the barrel and will not wear on its exterior face in its operation. The filling- 30 tube passes through a cross-wall 53^a of an annular flange or rim 53, in the chamber 54 of which is a packing 55, compressed by a gland or follower 56, threaded into the end of the annular rim or flange 53, so that by advancing 35 the gland or follower the packing will be forced against the exterior face of the filling-tube and made a close tight joint against the escape of pressure and liquid around the filling-tube. The upper end of the liquid-filling 40 tube 52 is threaded into an annular flange or rim 57 on the under side of a head 58, which head on its upper side has an annular flange or rim 59, into which is threaded the lower end of a piston-rod 60, and the piston-rod 60 45 at its upper end has a piston 61, which operates in a cylinder 62, which cylinder at its extreme upper end is closed by a cap 63 and a packing 64, so as to be tight against the escape of fluid-pressure. The lower end of the 50 cylinder 62 is threaded into an annular flange or rim 65, attached to the plate 24 by screws 66 or otherwise. Depending from the under side of the plate 24 is an annular wall or boss 67, having a cross-plate 68, through which the 55 piston-rod passes, and above the cross-wall 68 is a chamber 69, which opens into the lower end of the cylinder 62, and below the cross-wall 68 is a chamber 70, into which is threaded a thimble or bearing 71, furnishing a guide 60 for the piston-rod 60. The annular wall 67 on one side has a boss 72, in which and in the plate 24 is a passage 73, which opens into the lower end of the cylinder 62 for admitting fluid-pressure into the cylinder below the pis- 65 ton. The piston-rod passes through a thim-

ble or bearing 74, threaded into an annular flange or rim 75^a on a cross-head 75, and the cross bar or head 75 at each end has a socket 76, through which sockets the rods 36 pass, and the cross head or bar is locked in position 70 on the rods 36 by bolts 77 or otherwise, so as to be adjustable on the rod 36 for the cross head or bar to furnish a stop by striking against the end of the thimble or bearing-box 71, as shown in Fig. 2.

The liquid-filling tube 52 at its lower end in the arrangement shown is cut away, so as to form a recess 78, into which is entered the valve by which the discharge of the liquid is controlled. The valve shown consists of a 80 plug 79, having a tapered exterior face to enter the lower end of the liquid-filling tube, and a body 80 terminating in a threaded stem 81, leaving a shoulder at the base of the cone-shaped plug, against which shoulder a plate 82 abuts, and below the plate 82 is a packing 83 of any suitable material cylindrical in cross-section and held in a groove formed between the plate and a securing head or nut 84 threaded onto the stem 81, which packing allows 90 of the necessary yield to insure a tight closing of the discharge end of the filling-tube for the liquid when the valve is drawn into the end of the filling-tube. The valve is threaded onto the lower end of a rod 85, the upper 95 end of which is threaded into a pendant 86, suspended from a pivot 87 in the slot 88 of an arm 89, which arm and pendant are located in a chamber 58^a, formed within the head 58, as shown in Figs. 15 and 16. The arm 89 is 100 fixedly attached to a cross-shaft 90, which shaft is supported in journal-boxes in the side walls of the head 58, each journal-box consisting of a hollow plug 91, threaded into the side wall of the head 58 and having in its 105 chamber 92 a packing 93, compressed by a gland or follower 94, threaded into the end of the hollow plug, so that a tight joint is formed around the shaft 90 against the escape of liquid-pressure. Each end of the shaft 90 projects beyond its journal box or bearing and has secured thereto by a key or spline 95 the arm 96 of a forked lever 97, which lever at its outer or free end 98, as shown, is spread apart, so as to leave an open space, and, as 110 shown, the forked lever is made in two parts, but could be made in a single piece, if so desired. The forked lever 97 is held normally depressed by a roller 99, engaging with its upper edge, which roller is carried by spring- 115 arms 100, each spring-arm having a coil 101, which encircles a stud 102, projecting out from the side wall of the head 58, and the short end 103 of each spring-arm outside of the coil engages with a stud 104, projecting out from 120 the side wall of the head 58, so that with the upward movement of the forked lever 97 the spring-arms will be put under a tension which serves to return the forked lever to normal 125 position with the removal of the force by 130

which the lever was raised. The forked lever when in normal position and held in that position, as shown in Fig. 14, rocks the shaft 90 and raises the outer or free end of the arm 5 89, raising the pendant 86, and with it the rod 85, drawing the valve at the lower end of the discharge-tube 52 tightly into place against the end of the tube and shutting off the flow of liquid through the tube. The initial descent of the cross-heads carries down the closing-head and the filling-tube 52, and the farther descent of the filling-tube through the downward travel of the piston 61 carries with it the head 58 and the parts connected therewith. The downward movement of the lever 97 continues with the downward movement of the head 58, and when the lever has reached a point where its under face contacts the end of a pin or stud 105, extending up from the 10 lug or head 33, the farther descent of the filling-tube and the head 58 raises the outer end of the lever 97 and rocks the shaft 90, bringing the parts into position shown in Fig. 15, by which the outer or free end of the arm 89 15 is carried down, carrying with it the pendant 86, forcing the rod 85 down and carrying the closing-valve away from the end of the discharge-tube 52, as shown in Fig. 15, leaving the end of the tube open for the free discharge 20 of the liquid into the package. This opening of the closing-valve for the liquid-filling tube does not occur until the filling-tube has entered the package and nearly reached the limit of its downward movement for the continued downward movement to the limit to 25 act and raise the free end of the lever 97 and open the valve, as just described.

The upper end of the cylinder 62 at a point above the limit of the upward travel of the 30 piston 61 has entered thereinto a pipe 106, connected by an elbow-coupling 107 with a short pipe 108, which in turn is connected by an elbow-coupling 109 with a pipe 110, the lower end of which enters an elbow-coupling 40 111 on the end of a connecting-pipe 112, the other end of which enters an elbow-coupling 113 on the end of a short pipe 114, entered into a flange or boss on the main controlling-valve. The shell or casing of the main 45 controlling-valve has a flange on the opposite side to the pipe 114, into which is entered the end of a pipe 115, connected by an elbow-coupling 116 with a short pipe 117, entered into an elbow-coupling 118, into which coupling is entered the lower end of a pipe 119, the upper end of which enters a coupling 120, connected with a coupling 121, from which a pipe 122 leads to an elbow-coupling 123 on the end of a short pipe 124 in communication 50 with the passage 73 for discharging fluid-pressure into the cylinder 62 below the piston 61 of said cylinder. The pipe 110 constitutes a lead-pipe between the main controlling-valve for the fluid-pressure and the top 55 of the cylinder, and the pipe 119 constitutes

a lead-pipe between the main controlling-valve and the lower end of the fluid-pressure cylinder, and the intermediate pipes and elbow-couplings serve only to bring the lead-pipes into proper relation with the main controlling-valve for the position of the valve, and it will be understood that the lead-pipes and the valve can be located and arranged in other ways and so as to dispense with some of the elbow-couplings and intermediate pipes 70 for making the connection between the lead-pipes, the valve, and the cylinder. 75

A fluid-pressure-supply pipe 125, leading from any suitable source of fluid-pressure, is connected at its end with a tube 126, communicating with the upper portion of the filling-tank for the liquid, as shown in Figs. 4 and 5. The fluid-pressure-supply pipe 125 has therein a coupling 127, to which is connected one end of a hose 128, the other end of which is 80 connected by a coupling 129 with a tube 130, the lower end of which is connected by an elbow-coupling 131 with a short tube 132, which in turn is connected by an elbow-coupling 133 with a tube 134, the lower end of which is entered into a boss or wall 135 on the upper side of the shell or casing 136 of the main valve, and it will be understood that the tube 134 is the lead-tube and the elbow-couplings and intervening tubes are for the purpose of connecting the lead-tube with the hose, arising from the location of the main valve in the arrangement shown. The main valve has a shell or casing 136, having at one end a flange 137 and a closed wall 138, extending out from which is a threaded stem 139, by means of which the valve is attached to one of the side bars 27 of the frame carrying the closing-head and the filling-tube, so that the valve is within easy reach of the operator. The opposite 100 end of the shell or casing 136 has a flange 140, adjacent to which is a plate 141, connected with the flange by screws 142, the heads 143 of which are countersunk in the face of the plate 141 in the arrangement shown. The plate 141 encircles a neck 144 at one end of the valve-plug 145, the body of which is tapered and enters a tapered chamber 146 in the shell or casing 136, as shown in Fig. 7. The shell or casing 136 of the main valve has on one side 110 a boss or wall 147, into which is entered the pipe 114, and on the opposite side the shell or casing 136 has a boss or wall 148, into which is entered the pipe 115, and the under side or bottom of the shell or casing 136 has a boss or wall 135, which, as shown, does not have any tube or pipe connected therewith, but is open to the air. The shell or casing 136 has therein a port 149, which communicates with the pipe or tube 114 at one end, and its other end by 115 the turning of the valve-plug 145 can be brought into communication with a curved passage 150 in the valve-plug, and the shell or casing 136 has therein a port 151, which communicates with the pipe or tube 115 at one 120

130

end, and its other end by turning the valve-plug 145 can be brought into communication with a curved passage 152 in the valve-plug. The shell or casing 136 has therein a port 153, which communicates at one end with the pipe or tube 134 and can be brought into communication at its other end with a passage 150 of the valve-plug, and the shell or casing 136 has therein a port 154, which at one end opens 5 into the chamber of the boss or wall on the underside of the shell or casing, and its other end can be brought into communication with the passage 152 of the valve-plug. The shell or casing 136 has therein a longitudinal passage 155, communicating at one end with the port 153 and communicating at its other end with a passage 156, inwardly leading toward the valve-plug 145 and in communication with a passage 157 on the exterior of the valve-plug, as shown in Figs. 7 and 9, and the shell or casing 136 has therein a longitudinal passage 158, one end of which communicates with the port 154 and at its other end is in communication with a passage 159, leading inwardly to the plug-valve 145 and in communication with a passage 160 in the exterior of the plug-valve, as shown in Fig. 9. It will be seen that the ports 153 and 154 have communication with the passages 150 and 152 in 10 the valve-plug 145 and also with the passages 157 and 160 in the valve-plug and that the ports 149 and 151 have communication with the passages 150 and 152 and can be brought into communication with the ports 153 and 154 by turning the plug-valve and that when the passages 150 and 152 are brought into communication with the ports 149 and 153 and 151 and 154 the passages 157 and 160 are also in communication with the ports 153 and 154, 15 making the main valve, in effect, an eight-way valve, for a purpose hereinafter described. The shell or casing 136 has therein a port 161, which can be brought into communication with the passage 157 by turning the valve-plug 145, as shown in Fig. 9, and this port is in communication with a nipple 162, attached to which is one end of a hose 163. The shell or casing 136 has therein a port 164, which can be brought into communication with the passage 160 by 20 turning the valve-plug 145 as shown in Fig. 9, and this port is in communication with a nipple 165, having attached thereto one end of a hose 166, so that when communication is established between the passage 157 and the port 153, fluid-pressure communication is established between the port 164 and the port 154, fluid-pressure from the hose 166 will discharge into the air.

The top of the filling-tank 3 has entered 25 thereinto a nipple 167, to which is attached one end of a hose 168, the other end of which is attached by a coupling 169 to the upper end of a pipe or tube 170, terminating at its lower end in a turned portion 171, which is connected to one end of a three-way coupling 172,

as shown in Fig. 11. The upper end of the three-way coupling 172 has entered thereinto a hollow stem 173, depending from the center of a plate or disk 174, having an annular flange or rim 175 around its periphery, into 70 which is threaded the lower end of a cylinder 176, the upper end of which cylinder is threaded into an annular flange or rim 177 around the periphery of a plate or disk 178, extending out from the center of which is a nipple 75 179, to which is attached the end of the hose 163, as shown in Figs. 1, 2, 3, and 11. The bottom plate or disk 174 on one side has therein a passage 180, which opens into the lower end of the cylinder 176, and this passage is 80 connected by a nipple 181 with the hose 166, as shown in Figs. 1, 2, 3, and 11. The cylinder 176 has located and operating therein a piston 182^a, consisting, as shown, of two cup-leathers 182 and 183, clamped between plates 85 184 and 185 by nuts 186 on the threaded end of a piston rod or stem 187, which piston-rod passes through the chamber 188 of the stem 173, in which chamber is a packing 189, compressed around the piston rod or stem by a gland or 90 follower 190 encircling the piston rod or stem and threaded into the hollow stem 173, so as to make a tight joint around the piston rod or stem against the escape of fluid-pressure. The piston rod or stem at its lower end has 95 fixed thereto a valve consisting of a disk 191, of rubber, leather, or other suitable material, carried by a disk or plate 192, having a peripheral rim or flange encircling the valve-disk and held in place on the piston rod or stem by a nut 193, so that the valve can be properly adjusted for use. The valve at the lower end of the piston rod or stem 187 closes the lower end of a hollow piston rod or stem 194, the upper end of which is threaded into 100 an end of the three-way coupling 172, as shown in Fig. 11. This hollow piston rod or stem 194 carries at its lower end a valve consisting, as shown, of a cup-leather 195, held between plates or disks 196 and 197, and, as shown, 105 the disk 197 has a flange or rim 198, with an interior screw-thread, by means of which the valve is attached to the piston rod or stem 194, and the two plates or disks 196 and 197, with the cup-leather between them, are united 110 one to the other by screws 199 in the arrangement shown. The piston of the hollow stem 194 is located and operates in a cylinder 200, preferably made of glass or other transparent material. The cylinder 200 is held between 115 an upper plate or disk and a lower plate or disk, and the upper plate or disk 201 has a depending peripheral rim or flange 202 encircling the upper end of the cylinder, and between the upper end of the cylinder and the under face of the plate or disk 201 is a packing 203, of any suitable material. The upper plate or disk 201 has extending up therefrom a neck 204, in which the hollow piston rod or stem 194 reciprocates, and the neck 204 has 120 125 130

an exterior screw-thread on which is entered a cap 205, which incloses a packing 206, which packing is compressed by advancing the cap so as to make a tight joint around the hollow 5 piston rod or stem against the escape of fluid-pressure. The lower plate or disk 207 of the cylinder 200 has a peripheral rim or flange 208, into which is entered the lower end of the cylinder 200, and between the end of the 10 cylinder and the upper face of the disk or plate is a packing 209, of any suitable material. The two disks or plates 201 and 207 are tied together by rods 207^a, extending up from the lower plate or disk and passing through 15 the upper plate or disk and receiving on their ends wing-nuts 207^b, by means of which rods and nuts the plates or disks are drawn toward each other, so as to compress the packing 202 and 209 at each end of the cylinder, making 20 a tight joint for the cylinder against the escape of fluid-pressure.

The lower disk or plate 207 has extending downwardly therefrom a neck 210, in which is a passage 211, communicating at its upper 25 end with the interior of the cylinder 200 and communicating at its lower end with the lateral passage 51 within the cross head or bar 35. The passage 211 is closed at its upper end by a valve coacting with a seat 212 around 30 the passage in the bottom plate or disk 207, and, as shown, the valve consists of a disk 213, of rubber, leather, or other suitable material, held by a plate 214, having a peripheral rim or flange within which the valve-disk 35 is located, and the disk or plate 214 is held between nuts 215 on a valve-stem 216, extending down through the passage 211 and encircled by a coiled spring 217, the lower end of which spring rests on a cross-pin 218 and tends to 40 hold the valve in its closed position. The bottom of the cross head or bar 35 has a rim or flange 219 surrounding a chamber 219^a, extending into the enlarged portion 42 of the cross head or bar, in which chamber and 45 around the valve-stem 216 is a plate or disk 220, beneath which is a packing 221 in the chamber, which packing is compressed around the stem by a gland or follower 222, threaded into the annular wall or rim 219, so that when 50 the packing is compressed a tight joint will be formed around the stem 216 against the escape of fluid-pressure.

The head 58 on one side has a port 223, encircled by a rim 224, into which is entered a 55 coupling 225 on the end of a hose 226, the other end of which hose is coupled to a nipple of a valve 227, entered into the bottom of the filling-tank, so that with the opening of the valve 227 liquid can flow from the filling-tank 60 into the chamber of the head 58 and discharge through the filling-tube 52 into the package when the valve controlling the discharge end of the filling-tube has been opened by the raising of the lifting-lever 97, as hereinbefore 65 described.

At one end of the filling-tank on the under side is entered a bushing 228, to which is connected a valve 229, the inlet side of which has entered thereinto a short tube 230, extending up from a plate 231, which is connected to a 70 plate 232 by rods 233 for the plates to retain between them a cylinder 234, of glass or other transparent material and constituting a sight-glass, and from the bottom of the plate 232 extends a short tube or nipple 235, to which 75 by means of a coupling 236 is attached a hose 237, leading to the supply for the beer or other liquid, so that by opening the valve 229 the beer or other liquid is free to flow into the filling-tank 3 to be taken therefrom by 80 the supply-hose for each filling apparatus and transferred to the package to be filled by means of the filling-tube.

The cylinder 200 has located in its bottom a vent-valve for supplying outside pressure 85 to fill the vacuum in the cylinder as the liquid flows out therefrom with the withdrawal of the filling-tube from the package. This vent-valve, as shown, consists of a rubber tube 238, slipped onto the end of a hollow 90 stem 239, which stem has an exterior thread for securing it in the bottom 207 of the cylinder 200, the stem having at its outer end a thumb-head 240, by means of which it can be advanced and reeded in the head 207, and extending through the stem and the head is a vent-hole 241, which allows pressure from the outside to act and open the walls of the tube 238 above the end of the stem, permitting air under atmospheric pressure to flow into the 100 cylinder 200 and fill the vacuum created by the withdrawal of the liquid, and thereby prevent explosive action with the withdrawal of the filling-tube. It will be understood that when fluid-pressure is passing through the 105 cylinder it will act and bring together the end of the tube above the end of the stem, making a tight joint against the admission of outside air, and with the admission of liquid into the cylinder 200 the liquid also serves to hold the 110 end of the rubber tube tightly closed, so that outside air cannot enter until a vacuum is created by the outflow of the liquid from the cylinder in the withdrawal of the filling-tube from the package.

The neck 144 of valve-plug 145 has extending out therefrom a squared end 242, onto which is entered the socket 243 of a handle 244, and, as shown, the handle is held on the squared end 242 by a washer 245, abutting 120 against the end face of the socket 243 and held in place by a screw 246, entered into the squared end or in any other suitable manner. The passages 150 and 152 and the passage 157 and 158 are so arranged, preferably, that when the handle is vertical the passages 150 and 152 are out of communication with the ports 149 and 153 for the passage 150 and the ports 151 and 154 for the passage 152, closing 125 the flow of fluid-pressure through these ports 130

and passages, and the passage 155 and 156 is out of communication with the passage 157, and the passage 158 and 159 is out of communication with the passage 160, shutting off the 5 flow of fluid-pressure through these several passages.

The handle 244 when in normal position stands vertical, or nearly so, in the arrangement shown, and with the handle 244 normal 10 the valve-plug is turned to shut off communication between the passages of the valve-plug and the ports in the shell or casing. The movement of the handle 244 forward to a slight extent turns the valve-plug 145 and 15 brings the passage 150 into communication with the ports 149 and 153, allowing pressure to flow from the filling-tank through the hose 128, pipe or tube 134, and pipe or tube 110 into the upper end of the cylinder 62 above 20 the piston, and at the same time the passage 152 is brought into communication with the ports 151 and 154, venting pressure from the cylinder 62 below the piston 61 by means of the pipe 119 to the atmosphere for the pressure 25 above the piston 61 to force down the closing-head sufficiently to close the bung or other filling-hole in the package. This initial turning of the valve-plug 145 brings the passage 157 into position to establish communication between the passage 155 and 156 and the port 161 for the pressure from the pipe or tube 134 to flow through the hose 163 into 30 the top of the cylinder 176 above the piston in said cylinder, forcing the piston down, and 35 with it the stem 187, opening the valve at the lower end of the hollow piston rod or stem 194, allowing pressure to flow from the pipe or tube 170 through the hollow piston stem or rod 194 into the cylinder 200 below the piston 40 in said cylinder, and the pressure so entering the cylinder 200 can flow through the passage 211, the valve of such passage being opened from the contact of the end of the stem 216 with the package into the passage 51, and 45 the chamber 50 to enter through the slots or passages 49, the package to be filled, equalizing the pressure between the filling-tank and the to-be-filled package, so that when the closing-valve of the filling-tube is opened the 50 liquid can flow into the package under an equalized pressure within the package and the filling-tank. The initial turning of the valve-plug 145 brings the passage 160 into position to establish communication between the passage 158 and 159 and the port 164, allowing 55 pressure below the piston in the cylinder 176 to escape through the passage 185 and hose 166 and discharge at the opening of the wall or boss 135^a to the atmosphere. This initial 60 turning of the valve-plug 145 for admitting and venting pressure as just described allows the sealing-head to descend and close the bung or other filling hole in the to-be-filled package, so that the fluid-pressure can enter the package 65 through the slots or passages 49 to equal-

ize the pressure between the filling-tank and package. The further movement forward of the handle 244 carries the passage 150 into full communication with the ports 149 and 153 and carries the passage 152 into full communication with the ports 151 and 154, as shown in Figs. 8 and 9. The pressure in the cylinder 62 below the piston 61 will now exhaust through the ports 157 and 154 and the passage 152, so that the pressure admitted 70 into the cylinder 62 above the piston 61 through the ports 149 and 153 and passage 150 will act and move the piston 61 downwardly in the cylinder, and such downward movement of the piston 61 through the piston rod or stem 60 forces down the head 58, and with it the filling-tube, for the lower end of the filling-tube to pass downwardly into the to-be-filled package, and when the head 58 in its descent has reached a point where the lever 97 engages the stop 105 the further descent of the filling-tube 52 opens the closing-valve at its end, allowing the beer to discharge 80 into the package. The full opening of the passages 150 and 152 leaves still open the passages 157 and 160, so that the fluid-pressure can flow through the passage 155 and 156, 85 passage 157, and port 161 to enter the hose 163 and pass into the top of the cylinder 176, holding the piston in said cylinder down and maintaining the valve at the end of the hollow stem or piston 194 open, and at the same time the passage 160 maintains communication between the passage 158 and 159 and the port 154 for venting pressure from below the piston in 90 the cylinder 176 through the hose 166 to the atmosphere.

The inflow of the liquid into the package as the liquid rises forces out the fluid-pressure in the package, and such pressure flows back 105 through the slots or passages 49 into the chamber 50 and out from the chamber 50 through the passages 51 and 211 into the bottom of the cylinder 200 and flows through the hollow stem or piston-rod 194 into the pipe 170 to 110 return to the filling-tank. The liquid when the pressure has been expelled completely from the package by the liquid filling the package follows the pressure and flows into the cylinder 200 through the slots or passages 49, chamber 50, passages 51, and passage 211, and when the liquid has entered the cylinder to a point where it reaches the face of the valve closing the lower end of the hollow stem or piston-rod 194 a further forward turning of the handle 244 carries the valve-plug 145 into position 115 to bring the passage 152 into communication with the ports 149 and 154, venting the pressure in the cylinder 62 above the piston 61 to the atmosphere. At the same time the 120 passage 150 is brought into communication with the ports 151 and 153, admitting pressure below the piston 61 in the cylinder 62 for the admitted pressure below the piston 16 in the cylinder 62 to act and initially 125 130

raise the piston in such cylinder, closing the valve at the lower end of the filling-tube by the throwing down of the lever 97 from the action of the spring-arms 100, and shutting off the flow of liquid into the filled package, so that the liquid can only rise in the cylinder 200 to the height of the piston in the cylinder 200, and it is to be understood that the piston in the cylinder 200 can be adjusted higher or lower and when adjusted remains in the position in which it is adjusted, forming an abutment against the flow of liquid into the cylinder 200 above the piston, maintaining an equalized pressure back of such piston. A still further forward movement of the handle 244 turns the valve-plug 145 into a position to establish full communication between the passage 150 and the ports 151 and 153, by which the pressure above the piston 61 in the cylinder 62 is fully vented to the atmosphere, and at the same time the passage 152 is brought into full communication with the ports 149 and port 154 for pressure to flow into the lower end of the cylinder 62 and raise the piston 61, withdrawing the filling-tube from the package. The upward movement of the filling-tube continues until the annular flange 59 abuts against the thimble 74, after which the continued upward movement of the piston 61 raises both the filling-tube and the closing-head in unison until the closing-head is clear of the package, at which time the liquid contained in the cylinder 200 has flowed back into the package, and the amount of liquid contained in the cylinder 200 below the piston therein should be sufficient to completely fill the package, for which purpose the position of the piston in the cylinder 200 should be adjusted accordingly. The further advance of the handle 244 to initially open communication between the ports 151 and 153 and the passage 150 to vent pressure from above the piston 61 and to initially open communication between the ports 159 and 154 and the passage 152 to admit pressure below the piston 61 to initially raise the filling-tube opens communication between the passage 160, the port 161, and the passage 158 and 159 to vent pressure from above the piston in the cylinder 176 for the pressure below the piston in said cylinder to act and raise the piston, closing the valve at the lower end of the hollow stem or piston-rod 194 and shutting off the flow of pressure and liquid into the hollow stem or piston-rod 194, so that the liquid will be held in the space of the cylinder 200 below the piston in such cylinder. The further turning of the handle to bring the valve-plug 145 into position for establishing a full communication between the ports 151 and 153 and the passage 150 and to establish full communication between the ports 149 and 154 and the passage 152 brings the passage 157 into full communication with the port 164 and the passage 155 and 156 for fully admitting pressure

into the cylinder 176 below the piston in said cylinder, the pressure entering through the port 164 and hose 166 and port 185 into the chamber of the cylinder 176 below the piston of said cylinder, and at the same time the passage 160 is brought in full communication with the port 161 and the passage 158 and 159 to vent the pressure above the piston in the cylinder 176 to the atmosphere, the pressure entering the port 161 through the hose 163, attached to the nipple 179 at the top of the cylinder. The handle 244 after the full return of the closing-head and filling-tube for the liquid is turned back to normal position, closing the several ports and passages of the main valve and bringing the valve and the parts into position for operation with the next package to be filled by again advancing the handle, as already described. The arrangement shown has between the end legs or standards 1 a platform 247, and to this platform is secured a series of standards or uprights 248, arranged in pairs, one pair for each filling apparatus. The pair of standards have journaled therein axles 249, on which are supporting-wheels 250, each having a beveled face, on which wheels is supported the barrel, keg, or other package 251, having a bung or other filling hole 252, through which enters the filling-tube 52 and which is to be closed by the closing-head when the package is to be filled with liquid. The operation is as follows: The package 251 to be filled is placed on the wheels 250 with the bung or other filling hole at the top, as shown on the left hand of Fig. 1. The closing-head and the filling-tube are raised, as shown on the left hand of Fig. 1, and the handle 244 is in normal position, so as to close all the ports and passages of the main controlling-valve. After the package is placed in position the handle 244 is turned to initially open communication between the ports 149 and 153 and the passage 150 to admit pressure to the cylinder 62 at its upper end above the piston 61 and to open communication between the ports 151 and 154 and the passage 152 to vent pressure from the lower end of the cylinder 62 below the piston 61, which allows the closing-head to descend and close the bung or other filling hole in the package. This main controlling-valve after it has been initially opened to cause the filling-tube and closing-head to descend sufficiently for the closing-head to seal the bung or other filling hole by a slight backward turning of the valve-plug brings the ports into the position shown in Fig. 10, in which position pressure is shut off from the cylinder of the filling-tube, but is free to flow into the package for equalizing the pressure, as at the same time the passage 157 is brought into position to establish communication between the port 161 and the passage 155 and 156 for pressure to flow through the hose 163 into the cylinder 176 above the

piston in said cylinder and to establish communication between the passage 160, the port 164, and the passage 158 and 159 to vent pressure through the hose 166 from the lower 5 end of the cylinder 176 below the piston in said cylinder. The downward movement of the piston in the cylinder 176 carries the valve at the lower end of the piston-rod 187 away from the lower end of the hollow stem or pis- 10 ton-rod 194, allowing pressure from the pipe or tube 170 to flow through the hollow stem or piston-rod 194 and enter the to-be-filled package through the passage 211, the passage 51, the chamber 50, and the slots or passages 49 15 to equalize the pressure between the filling- tank and the package. The further movement forward of the handle 244 to establish full communication between the ports 149 and 153 and the passage 150 admits full pressure to the 20 upper end of the cylinder 62 back of the piston 61 and at the same time establishing full communication between the ports 151 and 154 and the passage 152 to vent the pressure from the lower end of the cylinder 62 below the pis- 25 ton 61 for the pressure above the piston 61 to carry down the piston-rod 60, head 58, and filling-tube 52, entering the lower end of the filling-tube into the to-be-filled package. The contact of the lever 97 with the stop 105 as the 30 filling-tube nearly reaches the limit of its de- scent opens the valve at the lower end of the filling-tube, and with the conclusion of the de- scent of the filling-tube to its limit the valve at its lower end is fully opened for the liquid 35 to discharge into the package. The passage 157 is still in communication with the port 161, and the passage 155 and 156 and the passage 160 is still in communication with the port 164 and the passage 158 and 159, so that the valve 40 closing the lower end of the hollow stem or piston-rod 194 is held open, allowing the pressure which is forced out from the pack- age by the admission of the liquid to flow back through the slots or passages 49, chamber 50, 45 passage 51, passage 211, hollow stem or pis- ton-rod 194, and pipe or tube 170 into the top of the tank, thus maintaining the regulated pressure in the tank without the admission of additional pressure from the source of sup- 50 ply. The continued flow of the liquid into the package gradually fills the package, and when filled with the liquid the pressure will be completely forced out, and the further supply of the liquid will follow the pressure through the 55 slots or passages 49, chamber 50, passage 51, and passage 211 and enter the chamber of the cylinder 200 below the piston in said cylinder. The liquid is allowed to flow into the cylinder 200 until it reaches the under face of the valve 60 for the lower end of the hollow stem or pis- ton-rod 194, at which time the operator turns the handle 244 forward to initially establish communication between the ports 151 and 153, admitting pressure to the cylinder 62 below 65 the piston 61, and at the same time establish communication between the ports 149 and 154 and the passage 152 for venting pressure from the upper end of the cylinder 62 above the piston 61, so that the pressure below the pis- ton 61 will act and initially raise the filling- tube, releasing the contact of the lever 97 with the stop 105 for the spring-arms to act and close the valve at the lower end of the filling- tube, shutting off the supply of liquid. The initial establishment of communication be- 70 tween the ports 151 and 153 and passage 150 and between the ports 149 and 154 and the passage 152 establishes communication be- 75 tween the passage 157, the port 164, and the passage 155 and 156, admitting pressure to the 80 lower end of the cylinder 176 below the piston in said cylinder and at the same time estab- lishing communication between the passage 160, the port 164, and the passage 158 159, 85 venting pressure from the cylinder 176 above 90 the piston in said cylinder for the pressure below the piston in the cylinder 176 to act and raise the piston and close the valve at the lower end of the hollow stem or piston-rod, shutting off the flow of pressure and liquid into the hol- low stem or piston-rod. The establishment of full communication between the ports 151 and 153 and passage 150 and between the ports 149 and 154 and the passage 152 still maintains communication between the passage 157, port 95 164, and passage 155 and 156 and between the passage 160, port 161, and passage 158 and 159 for the admitted pressure below the piston in the cylinder 176 to hold closed the valve at the lower end of the hollow stem or piston-rod 194. The pressure admitted to the lower end of the cylinder 62 below the piston 61 con- 100 tinues to act, when full communication is es- tablished between the ports 149 and 154 and passage 152 and raise the piston 61, and such 105 upward movement of the piston 61 carries with it the piston-rod and its head 58, and with the contact of the head 58 with the cross- head 75 the further upward movement of the piston 61 raises the closing-head, with the fill- ing-tube, clear of the filled package. The closing - head can be swung backward out of the way for the insertion of the bung by 110 rocking the frame 17 on its end journals, and after the bung has been inserted the filled package can be rolled off from the support- ing-wheels and a new package placed in posi- 115 tion, and when in position the handle 244 can be again moved to cause the closing-head to descend and to admit pressure to the package 120 to equalize the pressure between the filling- tank and package and to cause the filling-tube to descend and open the valve at its lower end and when the package is filled cause the fill- ing-tube to initially rise, closing the valve at 125 its lower end, and to close the pressure-passage between the filling-tank and the filled package and to raise the filling-tube and closing-head out of and clear of the package. A new pack- 130 age is then placed in position, and these oper-

ations are continued until the supply of liquid is exhausted or until the required number of packages have been filled.

The port 153 is the main inlet-port, as it is always in communication with the source of pressure-supply, and the port 154 is the main outlet or discharge port, as it is always open to the air. The ports 149 and 151 are intermediate of the ports 153 and 154, and each port performs the office of a supply and exhaust port in itself—that is, pressure is free to flow in either direction through these ports, the direction of flow depending on the relation of the passages 150 and 152 to the ports 153 and 154 as to whether the ports 149 and 151 are induction or eduction ports. The passage 155 and 156 is an inlet-passage through its communication with the inlet-port 153, and the passage 158 and 159 is an outlet-passage through its connection with the port 154, while the ports 161 and 164 are both supply and exhaust ports, according as to their connection with the passages 157 and 160 and the connection of the passages 157 and 160 with the passage 155 and 156 and the passage 158 and 159. The several positions of the ports and passages in the main controlling-valve are illustrated in the outline figures from 17 to 26, both inclusive. Figs. 17 and 18 are companion ones and show the normal position of the plug-valve, in which position the ports 149, 151, 153, and 154 are closed against communication with the passages 150 and 152 and the ports 161 and 164 are closed against communication through the passages 157 and 160 with the passages 155 and 156 and 158 and 159—that is to say, the main controlling-valve is closed against the flow of pressure. Figs. 19 and 20 are companion ones and show the initial turning of the valve-plug 145 which brings into communication the ports 149 and 153 and the passage 150 and the ports 151 and 154 and the passage 152 and also brings into communication the passage 155 and 156, the port 161 and the passage 157, and the passage 158 and 159, the passage 160, and the port 164. Figs. 21 and 22 are companion ones and show the turning of the valve-plug 145 to bring into full communication the ports 149 and 153 and the passage 150 and the ports 151 and 154 and the passage 152 and also maintaining communication between the passage 155 and 156, ports 161 and passage 157, and passage 158 and 159, port 164, and passage 160. Figs. 23 and 24 are companion ones and show the further turning of the valve-plug to initially open communication between the ports 151 and 153 and the passage 150 and the ports 149 and 154 and the passage 152 and at the same time opening communication between the passage 155 and 156, port 164, and passage 157 and opening communication between the passage 158 and 159, port 161, and passage 160. Figs. 25 and 26 are companion ones, showing the valve-plug turned to bring into full communication the ports 151 and 153 and

passage 150 and the ports 149 and 154 and the passage 152 and maintaining the passage 155 and 156, port 164, and passage 157 in communication and the passage 158 and 159, port 161, and passage 160 in communication. It will be understood that the turning of the plug-valve is, in effect, continuous, as the initial communication for admitting pressure to the package is effected almost instantly with the passage of the valve-plug to its full position, (shown in Figs. 21 and 22,) and the initial communication of the ports and passages (shown in Figs. 23 and 24) is effected with the turning of the valve-plug to the full position, (shown in Figs. 25 and 26,) and the return movement of the valve-plug is a single movement back to the normal position, (shown in Figs. 17 and 18,) shutting off the flow of pressure.

The pressure returned to the filling-tank from the to-be-filled package as the liquid flows into the package is utilized in furnishing the requisite amount of pressure for operating the filling-tube and for equalizing the pressure between the filling-tank and the to-be-filled package, such return pressure taking the place of the pressure vented in the operation of the closing-head and the filling-tube and the piston in the cylinder 176, and with this arrangement the pressure returned to the filling-tank from the package is made use of instead of being vented, as is the practice in other filling apparatus for liquids. The weights 41, in connection with the weight of the rods, cross-heads, filling-tube, and closing-head, is sufficient to initially carry downward the closing-head for the closing-head to enter and seal the bung or other filling hole in the package, the filling-tube being carried down by the initial pressure back of the piston 61, so that its end will project into the package to be filled as the bung or other filling hole is sealed by the closing-head. The pipe or tube 170 serves as a supply-pipe to admit pressure to the cylinder 200 and also as a return-pipe for the pressure forced from the package by the liquid. The cylinder 176, with its piston, furnishes the means for controlling the valve by which pressure is inducted into the cylinder 200 and by which pressure is educted from said cylinder, and the cylinder 200 furnishes a receiver for the pressure in traveling both ways and also as a receptacle for containing a sufficient quantity of liquid to replace the liquid in the package displaced by the filling-tube. The cylinder 176, with its piston, is a controlling-cylinder for admitting and venting pressure to the cylinder 200, which cylinder is a pressure-cylinder by which pressure is supplied to the package to be filled and receives the pressure forced from the package by the inflow of the liquid thereinto. It will be seen that the control of pressure for operating the filling-tube and the control of pressure for equalizing the pressure between the filling-tank and the to-be-filled package are

both under one valve, such valve constituting a main controlling-valve for the pressure, and by this valve, with the initial opening thereof, the filling-tube and the closing-head descend, 5 and at the same time pressure is equalized between the filling-tank and the to-be-filled package, and that with the establishment of a full communication for carrying down the filling-tube and opening the closing-valve at the end 10 thereof to admit liquid to the package communication is maintained between the package and the filling-tank by which the pressure forced out from the package by the inflow of the liquid is carried back into the filling-tank, and that with the reverse of the flow 15 of pressure to the cylinder operating the filling-tube the outflow of pressure from the filling-tank in the direction of the package is shut off, thus maintaining the full pressure in 20 the tank. This arrangement of a single main controlling-valve enables the operator to work the apparatus quickly and effectually, as the only part requiring any special attention is the single main controlling-valve.

25 What I claim as new, and desire to secure by Letters Patent, is—

1. In a filling apparatus for liquids, the combination of a frame journaled at its ends to oscillate fore and aft, a plate journaled at its 30 sides to the frame to oscillate endwise, side bars depending from the plate, a cross-bar at the lower end of the side bars, guide-rods passing through the plate and the cross-bar, a cross-head on the lower end of the guide-rods, 35 a cross-head on the guide-rods below the oscillating plate for the oscillating frame and plate to properly center a closing-head and a filling-tube with the filling-hole of the to-be-filled package, a closing-head on the lower cross-head of the guide-rods, a reciprocating filling-tube for liquids 40 passing through the closing-head, a pressure-cylinder mounted on the oscillating plate, a piston in the pressure-cylinder, and a piston-rod connected with the piston 45 and with the filling-tube, substantially as described.

2. In a filling apparatus for liquids, the combination of end standards, a cross-bar extending from end standard to end standard, journal-boxes projecting from the cross-bar, a frame having a journal at each end to enter the journal-boxes of the cross-bar and permit the frame to oscillate fore and aft, journal-boxes on the sides of the frame, a plate having a journal on 50 each side to enter the journal-boxes of the frame and permit the plate to oscillate endwise, side bars depending from the plate, a cross-bar at the lower end of the side bars, guide-rods passing through the plate and the 55 cross-bar, a cross-head on the lower end of the guide-rods, a cross-head on the guide-rods below the oscillating plate for the oscillating frame and plate to properly center a closing-head and a filling-tube with the filling-hole of the to-be-filled package, a closing-head on the 60 cross-head of the guide-rods, a reciprocating filling-tube for liquids passing through the closing-head, a pressure-cylinder mounted on the oscillating plate, a piston in the pressure-cylinder, and a piston-rod connected with the piston and with the filling-tube, substantially as described.

lower cross-head of the guide-rods, a reciprocating filling-tube for liquids passing through the closing-head, a pressure-cylinder mounted on the oscillating plate, a piston in the pressure-cylinder, and a piston-rod connected with the piston and with the filling-tube, substantially as described. 70

3. In a filling apparatus for liquids, the combination of end standards, a cross-bar extending from end standard to end standard, journal-boxes projecting from the cross-bar, a frame having a journal at each end to enter the journal-boxes of the cross-bar and permit the frame to oscillate fore and aft, journal-boxes on the sides of the frame, a plate having a journal on each side to enter the journal-boxes of the frame and permit the plate to oscillate endwise, side bars depending from the plate, an ear on each side bar, an adjustable stop for each ear limiting the endwise oscillation of the plate, a cross-bar at the lower end of the side bars, guide-rods passing through the plate and the cross-bar, a cross-head on the lower end of the guide-rods, a cross-head on the lower 80 end of the guide-rods below the oscillating plate for the oscillating frame and plate to properly center a closing-head and a filling-tube with the filling-hole of the to-be-filled package, a closing-head on the lower cross-head of the guide-rods, a reciprocating filling-tube for liquids 85 passing through the closing-head, a pressure-cylinder mounted on the oscillating plate, a piston in the pressure-cylinder, and a piston-rod connected with the piston and with the filling-tube, substantially as described. 90

4. In a filling apparatus for liquids, the combination of a fore and aft oscillating frame, an endwise-oscillating plate carried by the frame, a closing-head connected with the endwise-oscillating plate, a reciprocating filling-tube passing through the closing-head, and means for causing the closing-head and the filling-tube to descend and have the oscillating frame and plate properly center the filling-tube and the closing-head with the filling-hole of the package to be filled, substantially 100 as described.

5. In a filling apparatus for liquids, the combination of a fore and aft oscillating frame, an endwise-oscillating plate carried by the frame, a closing-head connected with the endwise-oscillating plate, a reciprocating filling-tube passing through the closing-head, a pressure-actuated piston for the filling-tube and closing-head, and means for supplying pressure to actuate the piston, substantially as described. 115

6. In a filling apparatus for liquids, the combination of a fore and aft oscillating frame, an endwise-oscillating plate carried by the frame, a closing-head connected with the endwise-oscillating plate, a reciprocating filling-tube passing through the closing-head, a pressure-actuated piston for the filling-tube and closing-head, a cylinder in which the piston 125

is located, and means for supplying pressure to the cylinder, substantially as described.

7. In a filling apparatus for liquids, the combination of a suspended frame having both a fore-and-aft and a lateral oscillation, a cross-bar at the lower end of the frame, a slidable cross-head below the cross-bar and carried by the frame, a closing-head on the slidable cross-head, a reciprocating filling-tube for liquid 5 extending below the cross-bar at the lower end of the frame and through the closing-head, a head at the upper end of the filling-tube, means for reciprocating the filling-tube and its head, a valve controlling the discharge end 10 of the filling-tube, a valve-stem extending into the head of the filling-tube, means carried by the head of the filling-tube and engaging a stop on the cross-bar and connected with the valve-stem and automatically operated by engaging the stop with the descent of 15 the filling-tube to open the valve at the discharge end of the filling-tube, substantially as described.

8. In a filling apparatus for liquids, the combination of a suspended frame having both a fore-and-aft and a lateral oscillation, a cross- 20 bar at the lower end of the frame, a slidable cross-head below the cross-bar and carried by the frame, a closing-head on the slidable cross-

30 head, a reciprocating filling-tube for liquid extending below the cross-bar at the lower end of the frame and through the closing-head, a head at the upper end of the filling-tube, means for reciprocating the filling-tube and its head, a valve controlling the discharge end 35 of the filling-tube, a valve-stem extending into the head of the filling-tube, means carried by the head of the filling-tube and engaging a stop on the cross-bar and connected with the valve-stem and automatically operated by engaging the stop with the descent of 40 the filling-tube to open the valve at the discharge end of the filling-tube, and a spring for automatically returning the valve-stem and 45 its connected operating means to normal position and closing the valve at the discharge end of the filling-tube with the initial upward movement of the valve-stem, substantially as described.

50 9. In a filling apparatus for liquids, the combination of a suspended frame, a cross-bar at the lower end of the frame, a reciprocating filling-tube for liquids extending below the cross-bar, a head for the filling-tube, means 55 for reciprocating the filling-tube and head, a valve controlling the discharge end of the filling-tube, a valve-stem extending upwardly through the filling-tube and entering the head, a pendant within the head on the upper end 60 of the valve-stem, an arm within the head and having the pendant pivotally suspended therefrom, a rock-shaft having the arm fixed thereon, a lever for the rock-shaft on the outside of the filling-tube head, and a stop engaging 65 and raising the lever as the filling-tube ap-

proaches the limit of its descent for automatically opening the valve at the discharge end of the filling-tube, substantially as described.

10. In a filling apparatus for liquids, the combination of a suspended frame, a cross-bar 70 at the lower end of the frame, a reciprocating filling-tube for liquids extending below the cross-bar, a head for the filling-tube, means for reciprocating the filling-tube and head, a valve controlling the discharge end of the filling-tube, a valve-stem extending upwardly 75 through the filling-tube and entering the head, a pendant within the head on the upper end of the valve-stem, an arm within the head and having the pendant pivotally suspended therefrom, a rock-shaft having the arm fixed thereon, a lever for the rock-shaft on the outside 80 of the head of the filling-tube, a stop engaging and raising the lever as the filling-tube approaches the limit of its descent for automatically 85 opening the valve at the discharge end of the filling-tube, and means engaging the lever and automatically operating to close the valve at the discharge end of the filling-tube by depressing the lever, substantially as de- 90 scribed.

11. In a filling apparatus for liquids, the combination of a suspended frame, a cross-bar at the lower end of the frame, a reciprocating filling-tube for liquids extending below the 95 cross-bar, a head for the filling-tube, means for reciprocating the filling-tube and head, a valve controlling the discharge end of the filling-tube, a valve-stem extending upwardly 100 through the filling-tube and entering the head, a pendant within the head on the upper end of the valve-stem, an arm within the head and having the pendant pivotally suspended therefrom, a rock-shaft having the arm fixed thereon, a lever for the rock-shaft on the outside 105 of the head of the filling-tube, a stop engaging and raising the lever as the filling-tube approaches the limit of its descent for automatically 110 opening the valve at the discharge end of the filling-tube, a spring engaging the lever and operating to force the lever down when disengaged from the stop and automatically close the valve at the discharge end of the filling-tube, substantially as described.

12. In a filling apparatus for liquids, the 115 combination of a suspended frame, a cross-bar at the lower end of the frame, a reciprocating filling-tube for liquids extending below the cross-bar, a head for the filling-tube, means for reciprocating the filling-tube and head, a 120 valve controlling the discharge end of the filling-tube, a valve-stem extending upwardly through the filling-tube and entering the head, a pendant within the head on the upper end of the valve-stem, an arm within the head and having the pendant pivotally suspended therefrom, a rock-shaft having the arm fixed thereon, a lever for the rock-shaft on the outside 125 of the head of the filling-tube, a pin upwardly projecting from the bar and engaging and 130

raising the lever with the descent of the filling-tube and automatically opening the valve at the discharge end of the filling-tube, substantially as described.

- 5 13. In a filling apparatus for liquids, the combination of a suspended frame, a cross-bar at the lower end of the frame, a reciprocating filling-tube for liquids extending below the cross-bar, a head for the filling-tube, means 70 for reciprocating the filling-tube and head, a valve controlling the discharge end of the filling-tube, a valve-stem extending upwardly through the filling-tube and entering the head, a pendant within the head on the upper end 15 of the valve-stem, an arm within the head and having the pendant pivotally suspended therefrom, a rock-shaft having the arm fixed thereon, a lever for the rock-shaft on the outside of the head of the filling-tube, a pin 20 upwardly projecting from the bar and engaging and raising the lever with the descent of the filling-tube and automatically opening the valve at the discharge end of the filling-tube, a roller engaging the lever, and 25 a spring carrying the roller and operating as the lever is disengaged from the pin to carry down the lever and automatically close the valve at the discharge end of the filling-tube, substantially as described.
- 30 14. In a filling apparatus for liquids, the combination of a reciprocating cross-head, a closing-head carried by the cross-head, a suspended frame, a cross-bar at the lower end of the frame, a reciprocating filling-tube for liquid 35 passing through the closing-head, a head for the filling-tube, means for reciprocating the filling-tube and head, a valve controlling the discharge end of the filling-tube, a valve-stem extending upwardly through the filling- 40 tube and entering the head, a pendant within the head on the upper end of the valve-stem, an arm within the head and having the pendant pivotally suspended therefrom, a rock-shaft having the arm fixed thereon, a lever for 45 the rock-shaft on the outside of the head of the filling-tube, and a stop engaging and raising the lever as the filling-tube approaches the limit of its descent for automatically opening the valve at the discharge end of the filling-tube, substantially as described.

- 50 15. In a filling apparatus for liquids, the combination of a reciprocating cross-head, a closing-head carried by the cross-head, a suspended frame, a cross-bar at the lower end of the frame, a reciprocating filling-tube for liquid 55 passing through the closing-head, a head for the filling-tube, means for reciprocating the filling-tube and head, a valve controlling the discharge end of the filling-tube, a valve-stem 60 extending upwardly through the filling-tube and entering the head, a pendant within the head on the upper end of the valve-stem, an arm within the head and having the pendant pivotally suspended therefrom, a rock-shaft having the arm fixed thereon a le-

ver for the rock-shaft on the outside of the head of the filling-tube, a stop engaging and raising the lever as the filling-tube approaches the limit of its descent for automatically opening the valve at the discharge end of the filling-tube, and means for automatically closing the valve with the initial upward movement of the valve-stem, substantially as described.

16. In a filling apparatus for liquids, the combination of a reciprocating cross-head, a closing-head carried by the cross-head, a suspended frame, a cross-bar at the lower end of the frame, a reciprocating filling-tube for liquid 75 passing through the closing-head, a head for the filling-tube, means for reciprocating the filling-tube and head, a valve controlling the discharge end of the filling-tube, a valve-stem extending upwardly through the filling-tube and entering the head, a pendant within the head on the upper end of the valve- 80 stem, an arm within the head and having the pendant pivotally suspended therefrom, a rock-shaft having the arm fixed thereon, a lever for the rock-shaft on the outside of the head of the filling-tube, a stop engaging and raising the lever as the filling-tube approaches the limit of its descent for automatically opening the valve at the discharge end of the filling-tube, means for automatically closing the valve with the initial upward movement of the valve-stem, a port in the head for admitting liquid to the filling-tube, and hose connected with the port, and a filling-tank for liquid having the hose connected therewith, substantially as described.

100 17. In a filling apparatus for liquids, the combination of a suspended frame, a cross-bar at the lower end of the frame, slidable rods extending above and below the cross-bar, a cross-head on the lower end of the slidable 105 rods, a closing-head carried by the cross-head, a reciprocating filling-tube for liquid passing through the cross-head, a head for the filling-tube, means for reciprocating the filling-tube and head, a valve controlling the discharge 110 end of the filling-tube, a valve-stem extending upwardly through the filling-tube and entering the head, a pendant within the head on the upper end of the valve-stem, an arm within the head and having the pendant piv- 115 otally suspended therefrom, a rock-shaft having the arm fixed thereon, a lever for the rock-shaft on the outside of the head of the filling-tube, and a stop engaging and raising the lever as the filling-tube approaches the 120 limit of its descent for automatically opening the valve at the discharge end of the filling-tube, substantially as described.

18. In a filling apparatus for liquids, the combination of a suspended frame, a cross-bar 125 at the lower end of the frame, slidable rods extending above and below the cross-bar, a cross-head on the lower end of the slidable rods, a closing-head carried by the cross-head, a reciprocating filling-tube for liquid passing 130

through the cross-head, a head for the filling-tube, a pressure-cylinder, a piston within the pressure-cylinder, a piston-rod connected with the head of the filling-tube, a valve controlling the discharge end of the filling-tube, a valve-stem extending upwardly through the filling-tube and entering the head, a pendant within the head on the upper end of the valve-stem, an arm within the head and having the pendant pivotally suspended therefrom, a rock-shaft having the arm fixed thereon, a lever for the rock-shaft on the outside of the head of the filling-tube, and a stop engaging and raising the lever as the filling-tube approaches the limit of its descent for automatically opening the valve at the discharge end of the filling-tube, substantially as described.

19. In a filling apparatus for liquids, the combination of a suspended frame, a cross-bar at the lower end of the frame, slidable rods extending above and below the cross-bar, a cross-head on the lower end of the slidable rods, a closing-head carried by the cross-head, a reciprocating filling-tube for liquid, passing through the cross-head, a head for the filling-tube, a pressure-cylinder, a piston within the pressure-cylinder, a piston-rod connected with the head of the filling-tube, means for simultaneously and alternately admitting and withdrawing pressure from the cylinder, a valve controlling the discharge end of the filling-tube, a valve-stem extending upwardly through the filling-tube and entering the head, a pendant within the head on the upper end of the valve-stem, an arm within the head and having the pendant pivotally suspended therefrom, a rock-shaft having the arm fixed thereon, a lever for the rock-shaft on the outside of the head of the filling-tube, and a stop engaging and raising the lever as the filling-tube approaches the limit of its descent for automatically opening the valve at the discharge end of the filling-tube, substantially as described.

45 20. In a filling apparatus for liquids, a main pressure-controlling valve having in its casing a main inlet-port for pressure, a main outlet-port for pressure, a combined supply and exhaust port on two sides intermediate of the main inlet and outlet ports for pressure, a passage leading from the main inlet-port, a passage leading from the main outlet-port, a combined supply and exhaust port on two sides at the terminal ends of the passages leading from the main inlet and outlet ports, and having in its valve-plug passages furnishing communication between the main inlet and outlet ports and the intermediate supply and exhaust ports, and passages furnishing communication between the passages leading from the inlet and outlet ports and their terminal supply and exhaust ports, substantially as described.

21. In a filling apparatus for liquids, the combination of a tank for liquid and pressure,

a main pressure-controlling valve having in its casing a main inlet for pressure, a main outlet for pressure, a combined supply and exhaust port on two sides intermediate of the main inlet and outlet ports for pressure and having in its valve-plug passages furnishing communication between the main inlet and outlet ports and the intermediate supply and exhaust ports, a cylinder, a pipe leading from the upper end of the cylinder to one of the intermediate supply and exhaust ports of the main controlling-valve, a pipe leading from the lower end of the cylinder to the other intermediate supply and exhaust port of the main controlling-valve, a piston within the cylinder, a piston-rod for the piston, and a filling-tube connected with the piston-rod, substantially as described.

22. In a filling apparatus for liquids, the combination of a tank for liquid and pressure, a main pressure-controlling valve having in its casing a main inlet-port for pressure, a main outlet-port for pressure, a passage leading from the main inlet-port, a passage leading from the main outlet-port, a combined supply and exhaust port on two sides at the terminal ends of the passages leading from the main inlet and outlet ports, and having in its valve-plug passages furnishing communication between the passages leading from the inlet and outlet ports and their terminal supply and exhaust ports, a controlling-cylinder, a pipe leading from the upper end of the cylinder to the terminal port of the passage from the main inlet-port, a pipe leading from the lower end of the cylinder to the terminal port of the passage from the main outlet-port, a piston in the controlling-cylinder, a piston-rod for the piston, a pressure-cylinder in juxtaposition to the controlling-cylinder, a piston in the pressure-cylinder, a hollow piston-rod for the piston of the pressure-cylinder and through which the piston-rod of the controlling-cylinder extends, a valve on the end of the piston-rod of the controlling-cylinder, and a pipe leading into the hollow piston-rod of the pressure-cylinder, for supplying pressure to and exhausting pressure from the pressure-cylinder when the valve of the controlling-cylinder is open, substantially as described.

23. In a filling apparatus for liquids, the combination of a tank for liquid and pressure, a main pressure-controlling valve having in its casing a main inlet-port for pressure, a main outlet-port for pressure, a passage leading from the main inlet-port, a passage leading from the main outlet-port, a combined supply and exhaust port on two sides at the terminal ends of the passages leading from the main inlet and outlet ports, and having in its valve-plug passages furnishing communication between the passages leading from the inlet and outlet ports and their terminal supply and exhaust ports, a controlling-cylinder, a pipe leading from the upper end of the cylinder to the terminal port of the passage from the main

inlet-port, a pipe leading from the lower end of the cylinder to the terminal port of the passage from the main outlet-port, a piston in the controlling-cylinder, a piston-rod for the piston, a pressure-cylinder in juxtaposition to the controlling-cylinder, a piston in the pressure-cylinder, a hollow piston-rod for the piston of the pressure-cylinder and through which the piston-rod of the controlling-cylinder extends, 5 a valve on the end of the piston-rod of the controlling-cylinder, a pipe leading into the hollow piston of the pressure-cylinder for supplying pressure to and exhausting pressure from the pressure-cylinder when the valve 10 of the controlling-cylinder is open, a port in the bottom of the controlling-cylinder, a valve controlling the port, a closing-head for the filling-hole of the package and having therein a passage in communication with the port 15 of the pressure-cylinder for admitting and venting pressure from the package, substantially as described.

24. In a filling apparatus for liquids, the combination of a tank for liquid and pressure, 25 a main pressure-controlling valve having in its casing a main inlet-port for pressure, a main outlet-port for pressure, a passage leading from the main inlet-port, a passage leading from the main outlet-port, a combined 30 supply and exhaust port on two sides at the terminal ends of the passages leading from the main inlet and outlet ports, and having in its valve-plug passages furnishing communication between the passages leading from the 35 inlet and outlet ports and their terminal supply and exhaust ports, a controlling-cylinder, a pipe leading from the upper end of the cylinder to the terminal port of the passage from the main inlet-port, a pipe leading from the 40 lower end of the cylinder to the terminal port of the passage from the main outlet-port, a piston in the controlling-cylinder, a piston-rod for the piston, a pressure-cylinder in juxtaposition to the controlling-cylinder, a piston 45 in the pressure-cylinder, adjustable in the cylinder and when adjusted held in a fixed relation, a hollow piston-rod for the piston of the pressure-cylinder and through which the piston-rod of the controlling-cylinder extends, 50 a valve on the end of the piston-rod of the controlling-cylinder, and a pipe leading into the hollow piston-rod of the pressure-cylinder for supplying pressure to and exhausting pressure from the pressure-cylinder and regulating the quantity of liquid flowing into the 55 cylinder, substantially as described.

25. In a filling apparatus for liquids, the combination of a tank for liquid and pressure, a main pressure-controlling valve having in its casing a main inlet-port for pressure, a main outlet-port for pressure, a passage leading from the main inlet-port, a passage leading from the main outlet-port, a combined 60 supply and exhaust port on two sides at the 65 terminal ends of the passages leading from the

main inlet and outlet ports, and having in its valve-plug passages furnishing communication between the passages leading from the inlet and outlet ports and their terminal supply and exhaust ports, a controlling-cylinder, 70 a pipe leading from the upper end of the cylinder to the terminal port of the passage from the main inlet-port, a pipe leading from the lower end of the cylinder to the terminal port of the passage from the main outlet-port, a piston in the controlling-cylinder, a piston-rod for the piston, a pressure-cylinder in juxtaposition to the controlling-cylinder, a piston 75 in the pressure-cylinder, adjustable in the cylinder and when adjusted held in a fixed relation, a hollow piston-rod for the piston of the pressure-cylinder and through which the piston-rod of the controlling-cylinder extends, 80 a valve on the end of the piston-rod of the controlling-cylinder, a pipe leading into the 85 hollow piston-rod of the pressure-cylinder for supplying pressure to and exhausting pressure from the pressure-cylinder and regulating the quantity of liquid flowing into the cylinder, a port in the bottom of the pressure-cylinder, a valve controlling the port in the bottom of the pressure-cylinder, a closing-head for the filling-hole of the package and having therein a passage for liquid and pressure for admitting pressure to and exhausting pressure from the package and regulating the outflow of liquid, substantially as described.

26. In a filling apparatus for liquids, the combination of a tank for liquid and pressure, 100 a main pressure-controlling valve connected with the tank, a controlling-cylinder having a piston actuated by pressure passing through the controlling-valve, a pressure-cylinder having a piston operative from the piston of the 105 controlling-cylinder and receiving pressure thereinto from the tank and returning pressure to the tank therefrom, and a closing-head for the filling-hole of a package, having therein a passage in communication with the pressure-cylinder, substantially as described.

27. In a filling apparatus for liquids, the combination of a tank for liquid and pressure, a main pressure-controlling valve connected with the tank, a controlling-cylinder having a 110 piston actuated by pressure passing through the controlling-valve, a pressure-cylinder having a piston operative from the piston of the controlling-cylinder and receiving pressure thereinto from the tank and returning pressure to the tank therefrom, a cylinder having therein a piston actuated from pressure supplied through the main pressure-controlling valve, a reciprocating filling-tube actuated from the piston, and a closing-head for the 115 filling-hole of a package, having therein a passage in communication with the pressure-cylinder, substantially as described.

28. In a filling apparatus for liquids, the combination of a main pressure-controlling 120

- valve, a cylinder and piston for actuating a filling-tube, the cylinder having communication with the main pressure-controlling valve, a controlling-cylinder having communication 5 with the main controlling-valve, a pressure-cylinder opened and closed to the flow of pressure thereinto and therefrom by the controlling-cylinder, and a closing-head for the filling-hole of a package in communication with 10 the pressure-cylinder for actuating the filling-tube and controlling the admission of pressure into and the discharge of pressure from the package by one and the same valve, substantially as described.
- 15 29. In a filling apparatus for liquids, a closing-head for the filling-hole of a package and having a passage therein for liquid and pressure, a pressure-cylinder in communication with the passage of the closing-head for admitting pressure into the passage of the head and for venting pressure from and allowing liquid to flow through the passage of the head, and a vent-valve admitting atmospheric pressure into the pressure-cylinder as the liquid 20 flows out therefrom for the admitted atmospheric pressure to prevent explosive action and insure the discharge of the liquid from the pressure-cylinder, substantially as described.
- 25 30. In a filling apparatus for liquids, the combination of a tank for liquid and pressure, means for admitting pressure into the tank, means for admitting liquid into the tank, a main controlling-valve for pressure, means connecting the controlling-valve with the tank, a cylinder having therein a piston, a reciprocating filling-tube actuated from the piston of the cylinder, means connected with the controlling-valve for inducting pressure into and educting pressure from the cylinder through the valve to operate the filling-tube, a controlling-cylinder having a piston therein and having 30 at the end of its piston-rod a valve, means for inducting pressure into and educting pressure from the cylinder on opposite sides of the piston through the main controlling-valve, a pressure-cylinder having an inlet-port controlled by the valve of the controlling-cylinder, means for supplying pressure to the pressure-cylinder, and a closing-head for the filling-hole of a package, having therein a passage in communication with the pressure-cylinder and through which closing-head the reciprocating filling-tube passes, substantially as described.
- 35 40. the valve to operate the filling-tube, a controlling-cylinder having a piston therein and hav-

ing at the end of the piston-rod a valve, means for inducting pressure into and educting pressure from the controlling-cylinder on opposite sides of the piston through the main controlling-valve, a pressure-cylinder having the inlet-port controlled by the valve of the controlling-cylinder, and means for supplying pressure to the pressure-cylinder for the pressure to flow into a to-be-filled package and 45 equalize the pressure between the tank and the package, substantially as described.

31. In a filling apparatus for liquids, the combination of a tank for liquid and pressure, means for admitting pressure into the tank, 50 means for admitting liquid into the tank, a main controlling-valve for pressure, means connecting the controlling-valve with the tank, a cylinder having therein a piston, a reciprocating filling-tube actuated from the piston of the cylinder, means connected with the controlling-valve for inducting pressure into and educting pressure from the cylinder through the valve to operate the filling-tube, a controlling-cylinder having a piston therein and having 55 at the end of its piston-rod a valve, means for inducting pressure into and educting pressure from the cylinder on opposite sides of the piston through the main controlling-valve, a pressure-cylinder having an inlet-port controlled by the valve of the controlling-cylinder, means for supplying pressure to the pressure-cylinder, and a closing-head for the filling-hole of a package, having therein a passage in communication with the pressure-cylinder and through which closing-head the reciprocating filling-tube passes, substantially 60 as described.
